*Primary Examiner—Joel Sincavage**Assistant Examiner—T. Chase Nelson**(74) Attorney, Agent, or Firm—Bruce S. Shapiro; Michael P. Leary; Charles E. Yocum***(57) CLAIM**

The ornamental design for an impact wrench, as shown and described.

DESCRIPTION

FIG. 1 is a right front perspective view of an impact wrench showing a first embodiment of my new design.

FIG. 2 is a left side view thereof.

FIG. 3 is a right side view thereof.

FIG. 4 is a front view thereof.

FIG. 5 is a rear view thereof.

FIG. 6 is a top view thereof.

FIG. 7 is a bottom view thereof.

FIG. 8 is a right front perspective view of an impact wrench showing a second embodiment of my new design.

FIG. 9 is a left side view thereof.

FIG. 10 is a right side view thereof.

FIG. 11 is a front view thereof.

FIG. 12 is a rear view thereof.

FIG. 13 is a top view thereof; and,

FIG. 14 is a bottom view thereof.

The dashed lines and the areas within the dashed lines form no part of the claimed ornamental design.
